UNITED STATES PATENT OFFICE.

ADOLF B. KELLERMAN, OF NEW YORK, N. Y.

PACKING-FORM.

1,335,972.

Specification of Letters Patent.

Patented Apr. 6, 1920.

Application filed June 25, 1915. Serial No. 36,188.

To all whom it may concern:

Be it known that I, ADOLF B. KELLERMAN, a citizen of the United States, residing at New York, in the county of Bronx and State 5 of New York, have invented certain new and useful Improvements in Packing-Forms, of which the following is a specification.

This invention relates to a packing form, and one of the objects of the invention is to 10 provide a simple and inexpensive device intended to be inserted within a coat or other garment, to hold the same in its proper shape in transportation.

Another object is to provide a device of 15 the kind referred to which is provided with means for maintaining the bust portions of the garment in proper shape, and with other means for preventing the shifting or slipping of the garment in its box during transportation, so that the nether portions of the 20 garment will not be collapsed and wrinkled or creased.

Still another object of the invention is to 25 provide a device securing the objects set out above which may be economically manufactured from cardboard or other suitable flat stock, which may be shipped in the flat, and which is easily manipulated to give it its final form.

Other objects and aims of the invention, 30 more or less broad than those stated above, together with the advantages inherent, will be in part obvious and in part specifically referred to in the course of the following 35 description of the elements, combinations, arrangements of parts, and applications of principles constituting the invention; and the scope of protection contemplated will appear from the claim.

In the accompanying drawings, which are 40 to be taken as a part of this specification, and in which I have shown a merely preferred form of embodiment of the invention, Figure 1 is a plan view of the blank 45 as it appears in the flat; Fig. 2 is a similar view of the same after it has been manipulated into its finished form; Fig. 3 is an edge view, the subject-matter of Fig. 1; Fig. 4 shows the device of Fig. 2 as applied

within a garment; and Fig. 5 is a sectional view of the subject-matter of Fig. 4.

Referring to the numerals on the drawings, there is shown at 6 a generally oblong sheet which may be of cardboard, thin sheet metal, celluloid, or the like suitable flexible 55 material, provided at one end with an aperture 7, and slotted as at 8 and 9 to form two side wings 10 and a main or body portion 11. These side wings 10 are provided at their lower ends with interengaging portions, for instance a notch 12 on the one adapted to be engaged by a tongue 14 on the other, and the body portion 11 is intended to form an integral tail-piece 15. For purposes of shipping, the devices may 60 be left in the flat, as in Fig. 1, and when they are to be used they are manipulated by bending the two side wings 10 to the position shown in Fig. 2, with the tongue of the one entered into the slot of the other, 65 in which condition the device will be bulged out and given the proper fullness so that it may, when inserted into a garment, as shown in Figs. 4 and 5, maintain the bust-portions 70 thereof in proper relation. The tail-piece 75 15 is surrounded by the skirt portion of the garment, and when the packing form, with the garment thereon, is placed in a box (indicated by dotted lines in Figs. 4 and 5), the tail-piece 15 will prevent the collapsing of 80 the garment within the box, and so avoid crushing, wrinkling or creasing of the skirt or tail-portions of the garment. The aperture 7 may be utilized for suspending the 85 packing form, with a garment on it, from a hook or the like in place of the ordinary clothes hanger.

Inasmuch as many changes could be made in the above construction, and many apparently widely different embodiments of 90 my invention could be made without departing from the scope thereof, it is intended that all matter contained in the above description or shown in the accompanying drawings shall be interpreted as illustrative 95 and not in a limiting sense.

It is also to be understood that the language used in the following claim is in-

tended to cover all the generic and specific features of the invention herein described and all statements of the scope of the invention which, as a matter of language, 5 might be said to fall therebetween.

I claim:

A packing form made of a single piece of flexible material of generally oblong form consisting of a bust piece, a body portion

and a skirt piece, the body portion having 10 incisions along its sides to provide side arms, said side arms adapted to be overlapped and interlocked with each other over the body portion thereby shaping the bust piece while the said body portion and skirt piece remain flat.

In testimony whereof I affix my signature.
ADOLF B. KELLERMAN.
